UNITED STATES PATENT OFFICE.

MAURICE GOLDBERGER, OF FORT WAYNE, INDIANA.

METAL-MELTING FURNACE OR RETORT.

1,125,090.

Specification of Letters Patent.

Patented Jan. 19, 1915.

Application filed August 11, 1911. Serial No. 643,502.

To all whom it may concern:

Be it known that I, MAURICE GOLDBERGER, a citizen of the United States, and resident of Fort Wayne, in the county of Allen and 5 State of Indiana, have invented new and useful Improvements in Metal-Melting Furnaces or Retorts, of which the following is a specification.

My invention relates to improvements in 10 metal melting furnaces or retorts, and its object is to provide a cheap, durable and efficient furnace or retort in which the heating flame and air are prevented from coming into contact with the metal during the 15 melting process, thereby rendering the device non-oxidizing in its operation.

Another object is to provide means by 20 which the interior of the furnace or retort is uniformly heated, thereby prolonging the life of the crucible or other metal container and the lining of the furnace or retort.

Another object is to provide means by 25 which the heat within the device is retained and not wasted or lost upon opening the device for the insertion of subsequent charges.

Another object is to provide means by 30 which sufficient metal may be placed within the device to fill the crucible when melted, the portion of the metal which is outside the crucible being superheated by the heat of the device and melted as it passes into the crucible and without coming into contact with the hot gases of the furnace.

Another object is to provide means by 35 which the point of contact of the flame with the furnace or retort lining may be varied in order to prolong the life of said lining.

My invention consists in the novel construction, arrangement and combination of 40 parts hereinafter described and illustrated in the drawings.

Referring to the drawings Figure 1 is a 45 vertical section of a furnace or retort constructed according to my invention; Fig. 2, a plan view of the same partially broken away; Fig. 3, a vertical section of a tilting furnace or retort constructed according to my invention; Fig. 4, a plan view of the same; Fig. 5, a vertical section of a modified form of tilting furnace or retort provided with my invention and Fig. 6, a plan view of the same.

In the drawings (Fig. 1) the furnace or retort consists of a cylindrical shell 1 within 50 which is a lining of fire brick or other suitable fire-proofing material 2. A ring

or cap 3 forms the top of the furnace or retort and plate 4 forms the bottom. Suitable bolts (not shown) pass through the top ring, the lining and the bottom plate, 60 by which the ring and plate are secured to the lining. Near the bottom of the lining are two diverging ports which extend through the lining 2 and shell 1 at opposite sides of the same. One port 5 only is 65 shown in Fig. 1, and two ports 35 are shown in Fig. 3. These ports are preferably inclined downwardly toward the interior of the furnace or retort and are tangentially arranged relative to the inner 70 periphery of the lining. In these ports are two oil burner tubes 6 which, at their outer ends, are connected to a two-way valve or other suitable device 7 by which the flow of oil from the supply pipe 8 to the two 75 burners is controlled. Valve 7 is adapted to cut off either one of the burners and turn on the other at will. The flame from either burner strikes the bottom and lower portion of the side of the lining and, of 80 course, rises upwardly. A horizontal annular flue 9 is arranged in the upper part of the lining and has communication with the exterior air through port 10 formed in the lining 2 and shell 1. A suitable number of ports 11 connect the interior of the furnace or retort with flue 9, said ports being formed in lining 2. The heat and flame rising in the interior of the device exhaust through ports 11 into horizontal flue 9 from 85 which exhaust occurs to outside air through port 10, thereby producing a steady, uniform draft at all points about the periphery of the interior of lining 2, with the attendant uniform heating of the interior of the 90 device.

A suitable post or rest 12 in the bottom of the device serves to support a crucible 13 within the furnace or retort.

The bottom of the furnace or retort is 100 inclined toward a discharge port 14 which extends through lining 2 and shell 1 and terminates in a receptacle 14' which is in tight connection with the exterior of the furnace or retort. Receptacle 14' is provided with a wall 15 of fire brick, or other suitable material, and lined with metal or other suitable material 16. A cover 17 closely fits over the top of the receptacle and is provided with a depending rod 18 of 110 suitable material. Receptacle 14' serves to catch the metal which escapes into the in-

terior of the furnace or retort in case crucible 13 should break and by lifting up cover 17 and the rod 18 the contents of the receptacle which will adhere to rod 18 may be withdrawn from the receptacle without 5 any loss thereof.

On top of upper cap 3 is a ring 19 and above this ring is another ring 20. Between the two rings and secured thereto by bolts 21 is a funnel or charger 22, the inner or 10 small end of which engages or rests on the top edge of the crucible 13. Preferably the lower edge of the funnel is recessed to permit a portion of the same to enter the mouth 15 of the crucible whereby a close fit of the two parts is obtained to prevent any flame from reaching the interior of the crucible. Funnel 22 extends from the top of the crucible to the top surface of ring 19, consequently it tends to hold within the device 20 all the heat applied therein. It may be formed of the same material as the crucible, or any suitable material for the purpose.

25 On top of ring 20 is a cover or lid 23 which is hinged at 24 to ring 20. Lugs 25 are secured to ring 20 and are hinged to lugs 26 by bolts 26', which latter lugs are secured to cap 3. A counterweight 27 is 30 secured to ring 20. Cover 23 is secured in its closed position by a suitable lock 28 and a suitable lock 29 serves to secure rings 19 and 20 in their closed position on the furnace or retort. Lock 29 is shown in Fig. 1 35 as comprising a handle hinged to ring 20 and depending therefrom. Near its lower end is a laterally projecting lug 29^a which is adapted to engage the lower surface of a lug 3^a which projects outwardly from ring 40 or cap 3, when the handle is forced toward the cap.

To charge the furnace or retort it is only necessary to raise lid 23 and fill up the crucible with the material to be melted. Funnel 22 may be filled at the same time so that as the material in the crucible melts that in the funnel will be added to it. At the same time the material in the crucible is melting the material in the funnel will also 45 be heated by the heat within the furnace or retort since the funnel is within the latter. Consequently the material supplied from the funnel is practically at the melting point as it passes into the crucible. By this 50 arrangement enough material may be charged into the furnace or retort to fill the crucible when the melting process is completed. In case more material is to be added while the device is in operation it is only 55 necessary to raise lid 23 to admit the charge. No heat is lost in this operation since funnel 22 covers the interior opening of the furnace or retort and completely excludes all escape of the heat except through exhaust flue 9. To withdraw the crucible it is 60

only necessary to raise the unitary group of lid 23, rings 19 and 20 and funnel 22 on hinge 26' and the crucible may be elevated out of the furnace or retort by tongs or other convenient tool.

70 It is now apparent that the flame within the furnace or retort, due to the horizontal flue 9, is uniformly distributed within the furnace and consequently uniformly heats the crucible; that funnel 22 being wholly 75 within the furnace prevents all contact between the flame and the metal thereby preventing all oxidization of the metal and it prevents all loss of heat by obviating the necessity of opening the furnace to add 80 more material in order to fill the crucible with molten metal and at the same time prevents all loss of heat in case lid 23 is raised for any purpose during the melting process. It is also apparent that by manipulating 85 valve 7 the flame may be directed to opposite sides of the furnace at intervals, thereby increasing the certainty of uniform heating of the crucible and its contents and prolonging the life of the lining where the 90 flame first strikes it.

In Figs. 3 and 4 I illustrate the application of my invention to a tilting furnace or retort in which oil is used as fuel. In this type the furnace comprises a shell 30 having a suitable fire proof lining 31 in the bottom of which is a suitable post 32 for supporting the crucible 33. The crucible is provided with an elongated spout 34 which passes through an opening in the 100 lining and shell, and through which the molten metal is discharged when the furnace is tilted. Within the crucible and extending downwardly from the inner end of the upper side of the spout 34 is a septum 38^a which extends across the crucible and terminates above the bottom of the same. This septum serves as a means to require the molten metal in the bottom of the crucible to be discharged first through the 110 spout when the furnace is tilted and to hold back any impurities on the top of the metal. Near the bottom of the furnace are two openings 35 in which are supported two oil burner tubes (not shown) which are controlled by a valve similar to the structure 7 illustrated in Fig. 1. To the bottom of the furnace is secured a receptacle 36 having a cover 37 closing the open end. A rod 38 of suitable material is carried by cover 120 37 and projects into the receptacle. A passageway or port 39 connects receptacle 36 to the interior of the furnace and permits the contents of the crucible to flow into the receptacle should the crucible break in operation, where the metal will cling to rod 38, by which the metal may be withdrawn from the receptacle. Suitable hollow blocks 40 project inwardly from the surface of lining 31 and serve to hold crucible 33 in 125 130

position when the furnace is tilted. The furnace is rotatably supported on standards 41 by spindles and bearings 42, and any suitable means for rotating the furnace on 5 said standards will suffice. In Fig. 4 I show a worm gear connection 42 between crank shaft 43 and the furnace by which the latter may be rotated. The top of crucible 33 is preferably flush with the top of 10 the lining surrounding it, and in contact with the lining and crucible is a hinged portion composed of a shell 44 and lining 45 similar to shell 30 and lining 31. Lining 45 is provided with a horizontal annular 15 discharge flue 46 having a discharge port 47 to outside air and ports 48 in lining 45 connect the flue with the interior of the hinged portion. On the top of the shell 44 and lining 45 is suitably secured a cap ring 20 49 and above ring 49 and secured thereto are other rings 50 and 51. Between rings 50 and 51 is secured a funnel 52, the lower edge of which makes contact with the upper edge of the crucible. The lower surface of the 25 lining 45 contacts with the upper surface of lining 31. Secured to ring 51 is a hopper 53 having a door 54 in its side through which door material to be melted is inserted into the hopper, funnel and crucible. 30 The connection between the valve to control the burners and the fuel supply line will be flexible to permit the rotation of the parts as the furnace is tilted.

In the tilting furnace just described the 35 hinged portion is only elevated on its hinge 55 when the crucible is to be removed or inserted. The same saving in heat, uniformity of heating and non oxidizing features and all the other advantages are present 40 as in the stationary furnace above described.

In Figs. 5 and 6 I illustrate the application of my invention to a tilting furnace or retort in which coke is used as fuel. In 45 this furnace or retort there is casing 60 and fire brick lining 61 and in the bottom portion the grate 62, above which crucible 63 is supported, the fuel being supplied between, the lining and crucible as is now the usual 50 practice. Near the top of lining 61 is a horizontally disposed channel 64 which is connected to hollow trunnion 65 by port 66, which port is provided in lining 61 and casing 60. A suitable pipe 67 is supported in 55 hollow trunnion 64 and leads to a suitable blower 68, which blower is adapted to be driven by any suitable power mechanism, as electric motor 69. On the bottom of casing 60 is fixed a box or pit 70 having doors 71 60 on its lower side, a suitable opening 72 being provided in the bottom of the furnace beneath grate 62 to establish communication between the interior of the furnace and pit 70. A suitable number of vertical channels 65 or flues 73 are provided in lining 61 which

lead from channel 64 to pit 70 by which air blown into channel 64 by blower 68 is conducted under pressure into pit 70 and from it through grate 62 into the interior of the furnace thereby creating a forced draft for 70 the combustion of the coke. The furnace is rotatably supported by trunnions 65 and 73 on standards 74, the standards being suitably mounted. In the drawing I show the standards, the blower and motor mounted 75 on a truck 75 by which the entire device may be transported from place to place at will. The furnace may be rotated on standards 74 in any convenient manner, as by worm gearing 75 and crank 76. Crucible 63 is provided with a spout 63^a which rests in a suitable opening formed in lining 61 and extends to the exterior of the furnace. The upper edge or top of the crucible is preferably flush with the top of the casing. 80 Resting on the top of the lower section of the furnace just described and hinged at 77 to the same is a portion 78. This portion is composed of a casing 79 and lining 80 similar to casing 60 and lining 61 and is provided with a preferably tapered central opening 81. A horizontal exhaust flue 82 is provided in lining 80 which has connection to the exterior air by port 83 formed in lining 80 and casing 79 and has connection also by a suitable number of ports 84 with opening 81. On the top of the lining 80 is a flat ring 85 and above this ring is another ring 86. Between the two rings is secured the outer flange of a charging funnel 87, the lower end of which makes close contact with the upper edge of crucible 63, in the closed position. A lid 88 is hinged at 89 to ring 86 and a counter weight 90 is fixed to ring 86. The group consisting of ring 105 85, 86, funnel 87 and lid 88 are hinged at 91 to casing 79, whereby the group may be elevated on said hinge to withdraw or insert the crucible and insert fuel. The lid 88 is independently movable to insert material to 110 be melted and this, due to funnel 87, is accomplished without releasing any of the heat within the furnace. Funnel 87 also enables the user to insert a sufficient quantity of material which when melted will fill 115 crucible 63 with all the advantages before described. All the advantages are present with the application of my invention to this type of furnace or retort as are present in the preceding types above described.

In each case, above described, the funnel is within the combustion chamber of the device and performs the same function in each. It has the further advantage of preventing the escape from the crucible of any part of 125 the material into the combustion chamber. It is further apparent that no oxygen from the air can enter the crucible during the process of melting to oxidize the metal. The metal cannot absorb any of the oxygen 130

of the air and hence a purer quality of metal is produced than has heretofore been possible, whereby better castings can be made from the metal.

- 5 In the use of the air blast-coke burning furnace above described the air is conducted, as stated, through channel 64 and vertical flues or conduits 73 into pit 70. The air is thereby thoroughly dried as it passes 10 through said channels to the great advantage of the operation of the device. It is further apparent that since the exhaust is solely at the side of the device rather than at the top, as is now the common practice, 15 the attendant can operate the device with greater ease and comfort than has been heretofore possible.

I contemplate applying my invention to all types of metal melting furnaces or 20 retorts to which the same may be applicable, hence I do not wish to be limited to the precise details of construction and arrangement above described.

What I claim is:

- 25 1. In a device of the class described, the combination of a furnace casing, a crucible supported above the bottom of the casing, a combustion chamber, and a charging member supported by the walls of the casing and 30 tilttable thereon and making contact at its lower end with the top of the crucible, for preventing the escape of heat from the combustion chamber through the top of the device.
- 35 2. In a device of the class described the combination of a furnace casing, a crucible supported within the casing, a funnel-shaped member tiltably supported on the casing and making contact at its lower end 40 with the top of the crucible, substantially as described.
- 45 3. In a device of the class described, the combination of a furnace casing, a crucible supported within the casing, a hollow member making contact at its lower end with the top of the crucible and having a flared top and flange which extends over the top of the casing, two flat rings secured to opposite sides of the flange and hinged to the 50 casing, and a cover hinged to one of the flat rings.
- 55 4. In a device of the class described, the combination of a furnace casing, a crucible supported within the casing, a charging funnel-shaped member having its lower end in contact with the top of the crucible and having a laterally projecting annular flange

at its upper edge which extends over the top of the casing, means secured to the flange and hinged to the casing for tilting the 60 member, a cover hinged to the latter means, and a horizontally disposed cylindrical flue in the casing wall above the crucible having communication with the interior of the furnace and with the outside air, and surrounding 65 the member.

5. The combination of a furnace casing, a crucible supported within the casing, a charging funnel tiltably supported on the 70 casing and making contact at its lower end with the top of the crucible, a cover for the mouth of the funnel having a hinged connection to the casing, a combustion chamber between the casing and the crucible and a horizontally disposed flue within the cas- 75 ing wall having communication with outside air and with the combustion chamber.

6. The combination with a tilttable furnace casing of a crucible suitably supported within the casing, the crucible having a 80 spout which projects through the casing to the outside, a second casing hinged to the top of the first named casing and provided with a horizontally disposed flue within its 85 wall having communication with outside air and with the interior of both casings, a charging funnel carried by the second casing and making contact at its lower end with the top of the crucible and a cover for 90 the mouth of the funnel.

7. The combination with a furnace casing having an opening in its bottom, a grate over the opening, a crucible supported on the grate, a charging funnel having a hinged connection to the casing and making contact at its lower end with the top of the funnel, a flue horizontally disposed and having communication, with outside air and with the interior of the casing above the crucible, a flue horizontally disposed in the casing 100 wall and having communication with the outside of the casing, and a plurality of vertically disposed flues in the casing wall having communication with the last mentioned horizontal flue and with the opening in the 105 bottom of the casing for supplying a draft of air to the interior of the casing.

In witness whereof I hereunto sign my name in the presence of two witnesses this 9th day of August, 1911.

MAURICE GOLDBERGER.
